UNITED STATES PATENT OFFICE

JOHN M DEALY, OF ASTORIA, NEW YORK, ASSIGNOR TO MACARTHUR CONCRETE PILE CORPORATION, OF NEW YORK, N. Y., A CORPORATION OF DELAWARE

APPARATUS FOR THE FORMATION OF CONCRETE PILES IN SITU

Application filed June 3, 1929. Serial No. 367,945.

This invention relates to apparatus for use in the formation of concrete piles in situ, and, more particularly, to apparatus comprising core leaves adapted to be expanded and contracted by the longitudinal movement of a center-bar.

An object of the invention is to provide improved means for withdrawing the leaves of a collapsible core together with the center bar.

10 Another object is to provide apparatus of the character described which is of simple and sturdy construction, and which operates efficiently and with freedom from mechanical defects.

15 Other objects of the invention will in part be obvious and will in part appear hereinafter.

The invention accordingly comprises the features of construction, combinations of elements, and arrangement of parts, which will be exemplified in the constructions herein-after set forth and the scope of the application of which will be indicated in the claims.

20 For a fuller understanding of the nature and objects of the invention, reference should be had to the following detailed description taken in connection with the accompanying drawings, in which:

25 Figure 1 is a longitudinal section of a collapsible core embodying the invention, showing the same inserted in a pile casing, a longitudinal portion of the core being broken away;

30 Fig. 2 is an enlarged detail sectional view of the corehead, showing the parts in driving position;

35 Fig. 3 is a similar view, showing the parts in withdrawing position;

40 Fig. 4 is a detail, showing the connecting means as viewed from the right of Fig. 2; and

45 Fig. 5 is a plan view of the core.

The exemplified apparatus comprises a collapsible core, indicated generally at 10, of a type suitable to be sunk into the ground either alone or in conjunction with a thin sheet metal or similar shell, such as shown at 11, to form a cavity into which concrete may be poured for the formation of a concrete pile or the like. The exemplified core com-

prises a center-bar 12 and a plurality of core leaves 13 separated longitudinally so as to permit the same to be expanded against the inner surface of the shell during driving, and to be collapsed when the core is to be withdrawn, the core leaves being connected to the center-bar by suitable toggle links, as indicated at 14. In order to press the core leaves into their expanded position, the center-bar carries a series of wedge-members 15 having upwardly- and outwardly-inclined surfaces which are adapted to seat against the surfaces of cooperating wedging elements 16 on the core leaves.

55 A driving-cap 17 is suitably secured at 65 the upper end of the center-bar, as by means of screw-threads 18, and between this driving-cap and the core leaves there is interposed a driving-plate 19, which is mounted on the core leaves, by means of pins 20, in a manner to permit radial movement of the leaves. In the present instance, the driving-plate is provided with an external downwardly-extending flange 21 adapted to limit the expanding movement of the core leaves.

70 The invention contemplates the provision of means for connecting the driving-cap and the core leaves in such manner as to insure the withdrawal of the core leaves with the driving-cap and center-bar after the latter 80 elements have moved upwardly a sufficient distance to permit the collapse of the leaves. To this end, there is provided in the exemplified apparatus a series of pairs of pivotally-connected links 22 and 23, each link 22 85 being pivotally mounted on an element 24 projecting from the driving-cap, and each link 23 being pivotally connected with an element 25 projecting from one of the core leaves. The driving-plate 19 is formed with suitable recesses 26, into which the links 22 and 23 seat when these links are aligned by the upward movement of the driving-cap.

90 By the provision of such means, the withdrawal of the core leaves after the driving-cap and center-bar have moved up a given distance is assured, the links 22 and 23 carrying the weight of the core leaves during the withdrawal of the core from the ground. 95 These links, being exteriorly mounted, can 100

be readily replaced, when necessary. The seating of the links in the recesses 26, moreover, stiffens the construction during the withdrawing operation.

5 Since certain changes may be made in the above construction and different embodiments of the invention could be made without departing from the scope thereof, it is intended that all matter contained in the 10 above description or shown in the accompanying drawings shall be interpreted as illustrative and not in a limiting sense.

It is also to be understood that the following claims are intended to cover all of 15 the generic and specific features of the invention herein described, and all statements of the scope of the invention which as a matter of language might be said to fall therebetween.

20 1. Pile-driving apparatus, comprising a center bar, a plurality of core leaves about said center bar, means for causing the collapse of said core leaves, means to cause the expansion of said core leaves, a driving cap 25 carried at the upper end of said center bar, and means connecting the upper end of each core leaf with said driving cap and independent of said collapsing means for supporting each core leaf from the driving cap 30 when in collapsed position, said means being collapsible to permit a limited longitudinal movement of the core leaves with respect to the center bar.

35 2. Pile driving apparatus, comprising a center bar, core leaves collapsibly associated with the center bar, a driving cap secured to the upper end of said center bar, and a plurality of pairs of pivotally connected links, one of each pair of said links being 40 pivotally connected with said driving cap, and another of each pair of said links being pivotally connected with one of said core leaves, said links being so arranged that when the same are in extended position they 45 will support the core leaves in collapsed position.

3. Pile driving apparatus, comprising a center bar, core leaves collapsibly associated with the center bar, exteriorly mounted collapsible suspension means, and means to connect said suspension means with said center bar and with said core leaves.

50 4. Pile driving apparatus, comprising a center bar, core leaves collapsibly associated with the center bar, means at the upper end of the center bar for applying thereto driving pressure and withdrawing pull, and collapsible elements attached to each core leaf at the outside thereof and connected with the upper end of said bar for suspending said core leaves from said center bar.

55 5. Pile driving apparatus, comprising a center bar, core leaves collapsibly associated with the center bar, a driving cap secured to the upper end of said center bar, sus-

pension means attached to the core leaves at the outside thereof, and means on said driving cap for supporting said suspension means.

6. Pile driving apparatus, comprising a center bar, core leaves collapsibly associated with the center bar, a driving cap secured to the upper end of said center bar, an outwardly extending element on each of the core leaves, outwardly extending elements on the driving cap overhanging the aforesaid elements, and collapsible suspension means connecting each pair of said outwardly extending elements.

7. Pile driving apparatus, comprising a center bar, core leaves collapsibly associated with the center bar, a driving cap attached to the upper end of the center bar, a driving plate fitting between said center bar and said core leaves, said driving plate being formed with recesses in its outer surface, and means to connect said driving cap with said core leaves, said connecting means being arranged to permit inward and outward movement of the core leaves, and being adapted to fit into said recesses.

8. Pile driving apparatus, comprising a center bar, core leaves collapsibly associated with the center bar, a driving cap attached to the upper end of the center bar, a driving plate fitting between said center bar and said core leaves, said driving plate being formed with recesses in its outer surface, and collapsible means for suspending each of said core leaves from said driving cap, said means being adapted when extended to fit into said recesses.

9. Pile driving apparatus, comprising a center bar, core leaves collapsibly associated with the center bar, a member carried at the upper end of said core leaves and formed with an external slot, and means connecting the center bar with the core leaves and including external elements adapted to fit into the slots of said slotted member.

10. Pile-driving apparatus comprising a center bar carrying longitudinally-spaced wedging members, a driving cap attached to the upper end of the center bar, a plurality of core leaves surrounding said center bar and formed with wedging members adapted to co-operate with the aforesaid wedging members, means to effect the collapse of said core leaves when said center bar is moved longitudinally, and means independent of said collapsing means for connecting said driving cap with said core leaves and adapted to permit a limited longitudinal movement between the two, said connecting means being adapted to support said core leaves from said driving cap, whereby supporting strain on the collapsing means is avoided.

In testimony whereof I affix my signature.
JOHN M. DEALY.
